STOKER

William Thompson Hanna, Cincinnati, Ohio

Original application November 6, 1928, Serial No. 317,621. Divided and this application August 6, 1936, Serial No. 94,499. Renewed May 6, 1939

5 Claims. (Cl. 198—15)

This invention relates to stokers in general but more particularly to stokers for use on locomotives and the like.

This application is a division of my copending application Serial No. 317,621, filed November 6, 1928, now Patent 2,077,791, issued April 20, 1937.

One of the objects of this invention is to provide a stoker which comprises a construction that acts to relieve congestion of the fuel preliminary to and within the crushing device, as well as after the crushing operation.

A further object of the invention is to provide fuel conveying means which transports the crushed fuel to the firing hole without excessive pulverization as is the case wherein knuckle joints and other mechanical interferences are present in the passages through which the fuel is conveyed.

Another object of the invention is to provide fuel conveying means which comprises a plurality of conveyers individually connected to driving means externally of the conduits in which the conveyers operate.

Another object of the invention is to provide a conveyer to feed fuel to the crushing device, said conveyer being power driven through a connection at its delivery end.

These and other advantages are attained by the means described in the following specification and disclosed in the accompanying drawings wherein:

Fig. 1 shows a sectional view of a stoker mechanism embodying this invention and taken substantially on a longitudinal center line.

Fig. 2 is a plan view of the mechanism shown in Fig. 1.

Fig. 3 is an external view of the entire stoker mechanism as viewed from the side opposite to Fig. 1.

Fig. 4 shows a modification in the arrangement of the conveyers as shown in Fig. 1.

In the drawings the back-head of a locomotive firebox is represented by the numeral 10, the firebox having the usual grate bars 11 and firing opening 12. Embracing said opening and rigidly mounted on the outer face of the back-head is a fuel supply housing 13, which is provided with a delivery opening 13—b coinciding substantially with the firing opening 12. Substantially in alignment with the opening 13—b in the opposite wall of said housing, is an opening 13—c which is embraced by a conventional form of fire-door plate 14, having an opening 14—a which serves as a fire-door opening, and upon which plate may be mounted the usual automatic fire-door (not

shown), such as for example the Franklin butterfly type.

The lower portion of the housing 13 is arranged in the form of a cylindrical conduit 13—e which surrounds the delivery end of a conveyer 23, the main portion of which is rotatively supported in a conduit 24 forming part of a sub-housing 24—a rigidly secured to the housing 13 and having an opening substantially flush with the deck 25 of the locomotive, through which fuel may be hand-fed directly to the conveyer 23 if desired. Positioned within the sub-housing 24—a is the delivery end of a conveyer 26 which is rotatively supported in a housing or conduit 27, the forward end of which has a universal connection with the sub-housing 24—a below the deck of the locomotive. The opposite end of the conduit 27 is slidably surrounded by a member 28 which is arranged to have a universal connection with a housing or conduit 29 rigidly secured to the front face of the tender hopper 30.

The design and construction of the housing or conduit 29 is of such a character that the cross-sectional area of the chamber within said conduit increases from the entrance at the tender hopper end to the portion which surrounds the member 28, thus the fuel passing through the conduit 29 is offered greater freedom as it approaches the conveyer 26 with the result that the tendency of the fuel to pack is minimized.

The tender hopper 30 is preferably in the form of a trough and is mounted in any suitable manner upon the tender 31, and in this instance is preferably arranged to incline toward the delivery end. Above the tender hopper 30 is the usual tender deck 31—a arranged so as to permit various areas thereof to discharge fuel into said hopper. Rotatively supported within the trough of the tender hopper 30 is a conveyer 32 which has its delivery end partially surrounded by a crushing member 33 which may be of any suitable character, but in this instance is shown as being rigidly secured to the inside front face of the tender hopper. The hub portion of the conveyer 32 is extended beyond the delivery end thereof and has a universal connection with the shaft 34 journaled in the wall of the conduit 29, and the opposite end of the conveyer is preferably confined in the trough by means of a retaining plate 35 rigidly secured to the trough 30.

The operating mechanism for the conveyers 23, 26 and 32 may be of any suitable character, but in this instance I have shown it as comprising a power-device in the form of a steam motor 36 like that disclosed in my U. S. Patent No.

1,577,462 in which the primary transmission element comprises a rack and pinion and it is this form of primary transmission element that I prefer to have embodied in the power device for operating a stoker of the character described herein, but it will be understood that other forms of transmission element may also be used effectively.

The power-device 36 is operatively connected with the conveyer mechanism by means of a suitable shaft 37 universally connected at one end to the power-device and similarly connected at its opposite end with a shaft 38 suitably supported for rotation on the tender hopper. A gear 39 is rigidly secured to the shaft 38 and meshes with a gear 40 rigidly secured to a shaft 41 suitably journaled on the conduit 29. The gear 39 also meshes with a gear 42 rigidly secured to the shaft 34. The shaft 41 is operatively connected with the conveyer 23 by means of a suitable shaft 43. Also, rigidly secured to the shaft 38 is a gear 44 which meshes with a gear 45 rigidly secured to a shaft 46 suitably journaled on the tender hopper 30. The shaft 46 is operatively connected to the conveyer 26 by means of the shaft 47.

The power-device, of whatever character, preferably should be provided with a control lever such as the lever 48 for starting and stopping rotation of the conveyers.

Such a stoker is preferably provided with means to more efficiently distribute the coal after it has passed through the firing opening 12 and for this purpose, I prefer a blast chamber of suitable type as 49 and a distributor plate 50 positioned at the entrance of the firebox immediately below the delivery opening 13—*b*—of the housing 13.

As shown in Fig. 1, it will be noted that as the fuel leaves the delivery end of the conveyer 26, it falls by gravity upon the conveyer 23 by which it is carried into the housing 13. In a modified form of the conveying mechanism, as shown in Fig. 4, I have arranged for feeding the fuel upwardly to a conveyer 51 which carries the fuel into the housing 13. In this modification, the conveyer 51 is mounted in a conduit 52 which forms a portion of a sub-housing 53, rigidly secured to the housing 13 and having an opening therein substantially flush with the deck 25 of the locomotive, through which fuel may be handed directly to the conveyer 51 if desired. On the underneath side of the sub-housing 53 is a housing or conduit 54, universally connected thereto, the said conduit surrounding the delivery end of a conveyer 55 which is mounted for rotation in a conduit 56, rigidly secured to the conduit 54, and having sliding engagement in a member 57 which is arranged to have universal engagement with a conduit 58, rigidly secured to the front face of the tender hopper 30 and similar to the conduit 29 previously referred to. The conduit 54 may be provided, on the under side, with an opening, normally closed as by a lid 54—*a*, by means of which the conduit may be emptied of fuel when desired.

The mechanism for operating this modified form of conveying mechanism, is similar to that previously described and shown, and comprises the shaft 37 operatively connected to the shaft 38 which in turn is geared to the shaft 34 by means of the gears 39 and 42, the shaft 38 also being geared to the shaft 46 by means of the gears 44 and 45 and the latter in turn operatively connected to the conveyer 55 by means of the shaft 47; but in this instance, the conveyer

51 is operatively connected to the shaft 34 by means of a shaft 59.

The operation of the stoker mechanism comprises the delivery of the fuel from the tender 5 to the locomotive by the conveyer 26 or the conveyer 55 and its reception therefrom by the conveyer 23 or the conveyer 51 by which the fuel is carried into the housing 13 and forced upwardly therein so as to flow over the facets of the members 15 and 16 and subsequently falling upon and flowing over the blast chamber 49 and the distributor plate 50.

It will be understood that the invention may be variously modified and embodied within the scope of the subjoined claims.

I claim:

1. A locomotive stoker mechanism for conveying fuel from a tender to a fire box comprising in combination, a hopper beneath said tender adapted to receive fuel therefrom, a screw conveyor in said hopper having a gear drive at its forward end only, a conduit forward of said hopper for delivering fuel to said fire box, a second screw conveyor in said conduit having its rearward end operatively connected with the forward end of said first-mentioned conveyor whereby said gear drive lies between the conveyors, a transfer conduit connecting the delivery end of said hopper with the rearward end of said first conduit to transfer the fuel around said gear drive, and a conveyor in said transfer conduit for moving fuel therethrough.

2. A locomotive stoker mechanism for conveying fuel from a tender to a fire box comprising in combination, a hopper beneath said tender adapted to receive fuel therefrom, a screw conveyor in said hopper having a gear drive at its forward end only, a conduit forward of said hopper for delivering fuel to said fire box, a second screw conveyor in said conduit having its rearward end operatively connected with the forward end of said first-mentioned conveyor whereby said gear drive lies between the conveyors, a transfer conduit connecting the delivery end of said hopper with the rearward end of said first conduit to transfer the fuel around said gear drive, a conveyor in said transfer conduit for moving fuel therethrough, a gear drive at the rear end of said last-mentioned conveyor, and means forming a geared connection between said gear drives whereby all of said conveyors are operated upon actuation of said first-mentioned gear drive.

3. A locomotive stoker mechanism for conveying fuel from the tender to the firing opening in a locomotive cab comprising, in combination, a hopper beneath the deck of said tender adapted to receive fuel from the tender bin, a screw conveyor in said hopper having a gear drive at its forward end, a transfer conveyor having its delivery end beneath the locomotive cab and its receiving end near the forward end of said first conveyor, a gear drive at one end of the transfer conveyor, a third conveyor located beneath the locomotive cab and positioned to receive fuel from said transfer conveyor, a gear drive at the rearward end of said third conveyor, means for driving one of said gear drives, and means forming a driving connection for all of said gear drives, whereby all conveyors are operated upon actuation of said driving means.

4. A locomotive stoker mechanism for conveying fuel from the tender to the firing opening in a locomotive cab comprising, in combination, a hopper beneath the deck of said tender adapted to receive fuel from the tender bin, a screw con-

veyor in said hopper, a transfer conveyor having its receiving end adjacent the forward end of said screw conveyor and its delivery end beneath the locomotive cab, a third conveyor beneath the locomotive cab and above the delivery end of said transfer conveyor, gear drives for said screw conveyor and transfer conveyor located at the forward and rearward ends thereof respectively, means forming a driving connection between the forward end of said screw conveyor and the rearward end of said third conveyor, means for driving one of said gear drives, and means forming a driving connection between said gear drives whereby all conveyors are operated upon actuation of said driving means.

5. A locomotive stoker for conveying fuel from the tender to the firing opening of a locomotive cab comprising, in combination, a hopper on said tender, a screw conveyor rotatably mounted in said hopper, the forward end of said hopper hav-

10 ing a delivery opening therein, a transfer conduit flexibly connected to said hopper adjacent said delivery opening so as to receive the flow of fuel therefrom, a transfer screw conveyor rotatably mounted in said transfer conduit, the forward ends of said transfer conduit and screw conveyor terminating adjacent the locomotive cab, a rotary drive for the front end of said hopper conveyor, a rotary drive for the rear end of said transfer conveyor, means for driving said first-mentioned rotary drive to rotate said hopper conveyor, gear means including a shaft rotatably mounted on said hopper and connected to said driving means for operation thereby, and means for universally connecting said shaft with the rotary drive on said transfer conveyor whereby operation of said driving means effects rotation of both the hopper conveyor and the transfer conveyor.
